UNITED STATES PATENT OFFICE.

RALPH H. WEST, OF CLEVELAND, OHIO.

MOLD FOR CASTING CHILLED ROLLS.

No. 894,925.

Specification of Letters Patent.

Patented Aug. 4, 1908.

Application filed December 26, 1906. Serial No. 349,452.

To all whom it may concern:

Be it known that I, RALPH H. WEST, a citizen of the United States of America, residing at Cleveland, in the county of Cuyahoga and State of Ohio, have invented certain new and useful Improvements in Molds for Casting Chilled Rolls; and I hereby declare the following to be a full, clear, and exact description of the invention, such as will enable others skilled in the art to which it pertains to make and use the same.

This invention relates to improvements in molds for casting chilled rolls.

The primary object of this invention is to provide a roll-casting mold which is beneficial in the manufacture of chilled rolls for obtaining castings which have all the requirements essential for the production of a chilled roll in which the chilled peripheral crust or shell of the roll-body is uniform in thickness circumferentially and from end to end of the roll, free from checks or cracks and other imperfections and found to be perfectly round when put in a lathe to be turned.

With this object in view, and to the end of realizing other advantages hereinafter appearing, my invention consists, first, in the provision of means whereby the upper mold-part or cope and a partition-forming head which forms a support for the loam or molding sand forming the surrounding wall or walls and bottom of the roll-neck-forming cavity of the drag not only can be lowered simultaneously to accommodate a descent of the casting while the chill and the drag-casing remain stationary but the said head is supported by a body of loose sand or similarly fluent or readily displaceable material which is contained within a chamber formed below the said head and a perforated bottom with which the drag-casing is provided under the said loose material with the perforations in the said bottom communicating with a receptacle operatively connected with the cope and arranged to receive material passing downwardly through the said perforations during the descent of the receptacle, and a lowering of the said receptacle by the descent of the cope will permit loose sand or fluent material to gravitate through the aforesaid perforations into the receptacle and thereby result in the lowering of the aforesaid head and any bodies of loam or molding sand forming the surrounding wall or walls and bottom of the drag-cavity, and conse-

quently accommodate the descent of the casting being produced in the mold; second, to automatically measure the distance which the cope lowers during the production of the casting; third, to provide an annular chill whose internal chamber not only extends from end to end of the chill but has its surrounding wall composed of superimposed alternately arranged solid and sectional rings which have such contour or shape internally that the casting is supported by the chill at suitable intervals vertically during and until after the contraction of the casting in the operation of the mold and the crust or shell of the roll-body-forming portion of the casting is accurately centered during the whole cooling or contraction of the casting; fourth, to provide a chill which is not only composed of superimposed rings convenient in the separation of the chill from the casting produced in the mold and provided internally with sloping seats arranged to center and support the roll-body but in which the roll-body-forming portion of the casting is entirely free from the sloping seat-forming surfaces formed internally of the solid chill-rings and is centered and wholly supported by the sectional chill-rings upon the completion of the cooling or contraction of the casting; fifth, to so support the cope that the roll-neck-forming metal in the cope can be readily lowered independently of the roll-body-forming portion of the casting during the operation of the mold to insure the formation of a good union between the roll-neck formed in and by the cope and the roll-body; sixth, to avoid undue strain during the upward expansion of the chill-composing rings upon the means employed in preventing upward displacement of the uppermost or top chill-ring; seventh, to provide simple and desirable means for automatically measuring the horizontal contraction of the roll-body-forming portion of the casting during the operation of the mold; eighth, to provide simple and meritorious means whereby the cope can be adjusted relative to the chill and the drag; ninth, to provide means whereby the aforesaid receptacle is detachably fastened to the drag-casing so as to accommodate an adjustment of the cope relative to the chill and drag without liability of disturbing the said receptacle; tenth, to provide simple and efficient means for interrupting continuity in the runner-gate or passage-way employed

in conducting molten metal to the drag-cavity, and eleventh, to attain other advantages which may hereafter appear.

In the accompanying drawings, Figure 1 is a side elevation of a roll-casting mold embodying my invention, and in this figure the mold is shown within a pit which is drawn in central vertical section, and portions are broken away and in section in this figure to more clearly show the construction. Fig. 2 is a top plan relative to Fig. 1. Fig. 3 is a vertical section in detail on line 3-3, Fig. 1, looking in the direction indicated by the arrow. Fig. 4 is a horizontal section in detail on line 4-4, Fig. 1, looking downwardly. Fig. 5 is a central vertical section on line 5-5, Fig. 2, looking in the direction indicated by the arrow. Figs. 6 and 7 are transverse sections on line 6-6 and line 7-7, respectively, Fig. 1, looking downwardly. Fig. 8 is a vertical section on line 8-8, Fig. 5, looking in the direction indicated by the arrow. Fig. 9 is a horizontal section on line 9-9, Fig. 8, looking downwardly. Figs. 3, 4, 8 and 9 are drawn on a larger scale than Figs. 1, 2, 5 and 6 which are drawn on the same scale.

My improved roll-casting mold comprises a lower mold-part or drag A, a central mold-part or chill B and an upper mold-part or cope C. The chill B (see Figs. 1, 5, 8 and 9) is stationary, being supported as will hereinafter appear. The chill B is annular and arranged vertically, having its roll-body-forming chamber b extending from end to end of the chill. The upper mold-part or cope C (see Figs. 2 and 5) is circular and provided centrally with a chamber 13 which extends vertically through the cope and is arranged centrally of the upper end of and in communication with the chill-chamber b. The cope C depends into and snugly but slidably fits within the upper end of the chill. The cope C is supported as will hereinafter appear from the chill in such a manner as to render the cope capable of being lowered within the chill.

The drag A (see Figs. 5 and 6) is provided with a cavity a arranged centrally of the drag and extending downwardly from the upper end of the drag a suitable distance. The cavity a is arranged centrally of the lower end of and in communication with the chill-chamber b. The body of the roll to be produced is cast in the chill B whereas the necks of the roll are cast in the drag and cope. The drag-cavity a and the cope-chamber 13 are of course enough smaller diametrically than the chill-chamber b and have the general outline required to form the necks of the roll to be cast.

The surrounding wall or walls of the upper end-portion of the drag-cavity a (see Figs. 5 and 6) are composed of a body of suitable sand or material such, for instance, as what is

known in the art as loam or loam-sand a', which body slidably fits internally of and is surrounded by a stationary metal casing E whose internal surface is smooth. The said body a' projects somewhat into the chill-chamber b and is detachably secured to the casing E by pins D which have bearing in the said casing and extend a suitable distance into the body a'. The pins D are withdrawable endwise from the body a' to detach the latter from the casing E and permit the said body to descend as will hereinafter appear with the body of loam-sand A' which forms the surrounding wall or walls of the lower portion and bottom of the cavity a. The body A' slidably fits within and is surrounded by the casing E which (see Fig. 5) also surrounds a head F which slidably fits internally of the said casing and forms a support for the said body A' of loam-sand. The head F is adapted to be lowered or shifted vertically downwardly within the casing E. The head F rests upon a body of loose sand or similarly readily displaceable or fluent material f which (see Figs. 5 and 7) is arranged within the casing E and below the head F, and the head F forms a partition between the body of material f and the lower of the superimposed bodies a' and A' of loam or molding sand.

The casing E (see Fig. 5) has a perforated bottom e which is instrumental in supporting the body of loose material f. The casing E is provided externally and next above the bottom e with an annular flange E' (see Figs. 1, 5 and 7) and the bottom e is formed by a circular head which is provided externally with an annular flange e' arranged next below the casing-flange E' and resting upon stationary posts or supports G. The bottom e is provided in its upper side with an annular recess e² whose side walls diverge upwardly. The bottom e is provided in its under side with an annular recess e³ whose side walls diverge downwardly. The recesses e² and e³ are arranged in line vertically. The perforations e⁴ formed in the head or bottom e extend vertically through the latter at the lower ends of the walls of the upper recess e² and establish communication between the recesses e² and e³.

A suitably supported receptacle H (see Figs. 1 and 5) slidably embraces the bottom e from below and is capable of being lowered, and any chamber or space formed between the perforated bottom e and the bottom of the receptacle H is filled with loose sand or similarly readily displaceable or fluent material g, and obviously the material f is displaced from above the bottom e through the perforations or passage-ways e⁴ into the receptacle H during the lowering of the receptacle. The receptacle H is operatively connected and consequently movable with the cope C as will hereinafter appear.

The cavity a is provided at one side and a

suitable distance below the upper end of the cavity (see Figs. 5 and 6) with an inlet for molten metal, and the mold is poured through the said inlet which is formed by the discharging end of a runner-gate which (see Figs. 1 and 6) has an upper upright portion a^3 and a lower portion a^2 which extends horizontally and laterally from the lower end of the upright portion through the drag-casing 5 E and at its inner and discharging end forms the inlet of the cavity a . The lower and laterally extending portion a^2 of the runner-gate has its inner end-portion preferably formed in the body of loam-sand a' and has 10 its outer end-portion surrounded by a casing E^2 which is formed on the drag-casing E at the lower end of the upright portion a^3 of the runner-gate, and the last-mentioned portion 15 of the runner-gate is surrounded by a casing E^3 which rests upon and is suitably attached to the casing E^2 .

The runner-gate-casing E^2 comprises a removable section E^4 arranged opposite the outer end of the laterally extending portion 20 a^2 of the runner-gate and externally of the lower end of the upright portion a^3 of the runner-gate. By removing the section E^4 access is had to the interior of the laterally extending portion a^2 of the runner-gate and to 25 the lower end of the upright portion a^3 of the runner-gate to facilitate the removal of the material forming the runner-gate. The casing-section E^4 is preferably detachably secured to the adjacent portions of the runner-gate-casings by suitably applied bolts and 30 nuts, as at I.

The lower or inner end-portion of the cope-chamber 13 (see Fig. 5) has the outline and dimensions required to form the inner end-40 portion of a roll-neck between the outer and wabble-forming end-portion of the said neck and the body of the roll, and the surrounding wall or walls of the said portion of the cope-chamber are formed by a body of loam-sand 45 14 built up within and surrounded by and supported in any approved manner from a metal casing K which constitutes the lower section of the cope-casing, and the remainder of the cope-chamber has the contour and dimensions required to form the wabble-forming outer end-portion of the said neck and to 50 form a feeding-head h above the wabble-casting portion of the said chamber, with the surrounding wall or walls of the feeding-head 55 and the wabble-casting portion of the cope-chamber built up of a body of loam-sand 15 within and surrounded by and supported in any approved manner from a metal casing k which constitutes the upper section of the 60 cope-casing. The casing-section k is seated on but removable from the top of the lower section K of the cope-casing. It will be observed therefore that the cope comprises an upper part which consists of the casing-section k and body of loam-sand 15 and a lower

part which consists of the casing-section K and body of loam-sand 14.

The upper cope-casing-section k (see Figs. 1, 2 and 5) is provided at its lower end and externally with laterally projecting lugs k' spaced circumferentially of the said cope-casing-section. Through each lug k' extends a screw J which is arranged with its head abutting against the upper side of the said lug, which screw has its threaded shank screwed into the flange K' . Obviously therefore the upper cope-casing-section is detachably secured to the lower cope-casing-section, and only the withdrawal of the screws J is required to accommodate the separation of the upper cope-part from the lower cope-part. The lower cope-casing-section and consequently the cope are supported from the chill as will hereinafter appear.

The chill B (see Figs. 1, 5, 8 and 9) is composed of superimposed metal rings arranged in line vertically, and the surrounding wall of the chill-chamber is formed by superimposed alternately arranged solid rings R and sectional rings r . Preferably each ring r is divided vertically into several corresponding and interchangeable sections, with the joints 22 spaced circumferentially of the ring. The chill is supported from the drag-casing E, as already indicated, and preferably the said 25 casing is provided at its upper end with a laterally and outwardly facing vertically arranged shoulder 16 which (see Fig. 5) is arranged concentrically relative to the drag-cavity a and snugly embraced by the flange 30 r' formed on and projecting downwardly from the outer portions of the sections of the lowermost sectional ring, which flanges are snugly embraced by the lower end of the lowermost solid chill-ring R which rests upon 35 the said casing and is accurately centered relative to the drag-cavity.

The uppermost or top chill-ring is formed by a solid ring R, and each solid chill-ring R (see Figs. 5, 8 and 9) is provided in its lower 40 end and internally with an annular recess 17 whose surrounding wall is beveled,—that is, slopes upwardly and inwardly,—which recess is snugly engaged by a sectional ring r which is preferably beveled externally to conform to the beveled surrounding wall of the said recess. Each sectional ring r , save the lowermost sectional ring, rests on the next lower solid ring. The lower end of the upper of adjacent solid rings R snugly embraces 45 the upper end of the lower of the said rings and rests upon an upwardly facing shoulder 18 formed externally of the said lower ring a suitable distance below the upper end of the last-mentioned ring. It will be observed 50 therefore that the chill-rings R and r are effectually locked together and to the drag-casing when the uppermost or top ring is prevented from upward displacement.

The opening which is formed in and ex- 55

tends vertically through each chill, and which forms a portion of the chill-chamber b , has an upwardly flaring surrounding wall which forms a downwardly and inwardly sloping seat-forming surface extending circumferentially of the chill, and the sloping seat-forming surface internally of each sectional ring is arranged below and flush at its upper end, as at 20, with and forms a downward extension 5 of the sloping seat-forming surface formed internally of the solid ring surrounding the said sectional ring. Obviously therefore the upper of adjacent sectional rings r overhangs the sloping seat-forming surface of the next 10 lower solid ring R .

Each section of each sectional ring to prevent warping of the same is (see Figs. 5, 8 and 9) provided at the bottom of its outer portion with a downwardly projecting flange 20 r' extending between the ends of the said section and having its inner surface vertical, and the flange r of the sections of the upper of adjacent sectional rings snugly overlaps a laterally and outwardly facing vertically arranged 25 shoulder R' which is formed upon the next lower solid ring above the upwardly facing shoulder 18 of the said solid ring and between the last-mentioned shoulder and the sloping seat formed internally of the said 30 solid ring.

By the construction hereinbefore described it will be observed that the chill is provided internally with vertically spaced downwardly and inwardly sloping seats extending circumferentially of the chill; that the chill comprises solid rings which are arranged in line vertically; that each solid ring is provided at its lower end and internally with a recess extending circumferentially of the 35 chill; that each solid ring is also provided internally next above the said recess with a downwardly and inwardly sloping seat-forming surface extending circumferentially of the chill and participating in the formation 40 of the surrounding wall of the chill-chamber b ; that the sectional ring which occupies the said recess is provided internally with a downwardly and inwardly sloping seat-forming surface, and the sloping seat-forming surface, 45 of each sectional ring is smaller diametrically than the sloping seat-forming surface of the solid ring which embraces the said sectional ring; that the sectional rings, being divided vertically into sections, facilitate the 50 separation of the chill-rings from the casting; that the upper of adjacent sectional rings rests upon the next lower solid ring; that the lower of adjacent solid rings is provided externally with an upwardly facing shoulder 18 55 extending circumferentially of the chill and forming a bearing for the upper of the said adjacent solid rings; that each of the internal downwardly and inwardly sloping seats of the chill is formed by a plurality of suitably supported rings extending circumferentially 60 65

of the chill; that the lower portion of each of the said seats is formed by a sectional ring; that the upper portion of each of the said seats is formed by a solid ring; that the upper of adjacent sectional rings is overlapped on top by the solid ring embracing it; that the relative dimensions of the seat-forming surfaces of the solid rings and the seat-forming surfaces of the sectional rings are such that the casting produced in the mold shall after 70 wholly cooling or contracting rest only upon the seat-forming surfaces of the sectional rings, and that warping of the sections of the sectional rings is successfully prevented.

Each sectional chill-ring r (see Fig. 8) is 80 preferably rounded, as at 24, at the junction of the lower end of its sloping seat-forming surface with the bottom surface of the ring.

A chill made as hereinbefore described is simple and inexpensive in construction and 85 an independent renewal of different portions of the chill is readily accommodated.

Each solid chill-ring below the uppermost solid chill-ring is provided in its upper end with grooves or recesses 29 arranged radially and spaced circumferentially of the chill-ring, which grooves or recesses form holes at the joint between the said chill-ring and the next upper sectional chill-ring for the escape 90 of air and gases from interiorly of the chill 95 during the pouring and operation of the mold, said grooves or recesses extending to the outer circumferential surface of the solid ring in which they are formed, but only into close proximity and not to the internal sloping seat-forming surface of the last-mentioned ring so as to positively avoid the ingress of molten metal into the said recesses 100 during the pouring of the mold without preventing the escape of air and gases from 105 within the chill into the said recesses because the joint formed between each sectional ring and the next lower solid ring is not air-tight and consequently loose enough at the inner ends of the said recesses to accommodate 110 the said escape of gases and air.

The slope of the lower of two adjacent sloping seats is less than the slope of the upper of the said seats so that the slant of the lower of the said seats is at a greater acute 115 angle to a horizontal plane than the upper of the said seats as not only clearly but exaggeratedly indicated by the illustrative dotted lines d in Fig. 8. The contracting casting is therefore accurately centered relative to and 120 from end to end of the chill by the said seats during and until after any lowering of the casting while the casting is cooling or contracting. In casting a roll by my improved mold the peripheral crust or shell of the casting formed in the chill is during and upon its contraction maintained in a strictly central position relative to the chill and supported circumferentially of and upon the aforesaid sloping seats. The casting is supported 125 130

ported until and after its final contraction at as many intervals vertically as there are sloping seats provided for the casting internally of the chill so that the said shell or crust is not liable to be cracked or put out of round or rendered defective by the pressure of molten metal within and centrally of the casting.

The lower cope-casing-section K and consequently the cope (see Figs. 1, 2 and 5) is adjustable vertically as will hereinafter appear, and, as already indicated, supported from the chill. The flange K' (see Figs. 1 and 5) of the said cope-casing-section K overhangs lugs 25 which are formed externally of the uppermost or top chill-ring R and spaced circumferentially of the chill. Through each lug 25 loosely extends a suitably supported vertically arranged rod L, and consequently several upright rods L are arranged externally and spaced circumferentially of the chill. The rods L extend loosely through holes 26 formed in lugs 27 formed on and externally of the upper end of the drag-casing E and are screw-threaded at their lower ends under the last-mentioned lugs, and correspondingly threaded nuts l (see Figs. 1 and 5) are mounted on the shanks of the said bolts next under the said lugs. The nuts l prevent upward displacement of the rods L which (see Figs. 5 and 6) are square or angular in cross-section where they extend through the lug-holes 26 which are correspondingly angular and conform to the said angular portions of the rods to prevent turning of the rods.

Each rod L is screw-threaded from the upper side of the chill-lug 25 through which the rod extends to the upper end of the rod, and a correspondingly threaded nut m (see Figs. 1 and 5) is mounted on the said rod above and rests on the said lug, but a block or piece n of wood or similarly somewhat compressible material is interposed between the said lug and the said nut. Obviously therefore the rods L are supported from the uppermost chill-ring through the medium of the nuts m and compressible members n, and obviously the said compressible members 50 and nuts prevent upward displacement of the said chill-ring. The compressible members n prevent undue strain upon the rods L and nuts m and l by any tendency of the chill to expand upwardly during the operation of the mold.

Cope-supporting nuts O (see Figs. 1, 2 and 5) are mounted on the upper portions of the rods L and loosely engage and are turnable within holes 28 formed in the flange K' of the lower cope-casing-section K. Each nut O is provided at its lower end and externally and below the said flange with an upwardly facing annular shoulder O' which forms a seat for anti-friction balls O² which are interposed between the said shoulder and the flange

K' so that the cope rests upon anti-friction bearings.

The chill B (see Figs. 4 and 5) is provided in its lower portion with a hole 30 which extends laterally from the interior to the exterior of the chill, which hole is formed partially in the lowermost solid chill-ring R and partially in the under side of the adjacent portion of the second lowermost solid chill-ring and is somewhat enlarged at its inner end, as at 32. A horizontally arranged bar or member P engages the hole 30 and is shiftable inwardly. The member P extends a suitable distance outwardly beyond the exterior of the chill and is provided at its inner end with a head P' which engages the enlarged inner end 32 of the hole 30 and is beveled and arranged flush in its outer and normal position with the sloping seat of the lowermost solid chill-ring. The head P' obviously therefore forms a stop for limiting the outward movement of the member P.

The endwise shiftable member P is arranged to be engaged at its outer end (see Figs. 1 and 4) by a suitably supported horizontally arranged slide Q which engages a correspondingly arranged slideway 33 formed in a bracket 34 which is suitably secured to the adjacent wall of a pit 35 in which my improved mold is arranged and operated. The slide Q is operatively engaged by the lower end of a lever T which extends through a slot Q' in the slide and is fulcrumed, as at 36, to the said bracket a short distance above the travel of the slide Q and horizontally and at a right angle to the said travel. The lever T extends upwardly to and above the upper end of the pit 35 and terminates at its upper end in a pointer t arranged to coöperate with a scale or graduated surface 37 formed on one side of a bracket u which is supported in any approved manner from the adjacent wall of the pit. The pointer t and scale 37 co-operate in measuring and indicating the distance which the gage-forming member P is moved into the chill-chamber upon the swinging of the lever by the action of a suitably applied weight w in the direction required to move the said gage-forming member into the chill. The bracket u (see Figs. 1 and 3) is slotted below and longitudinally of the scale, as at 38, and the slot 38 is engaged by a bolt 40 which is arranged with the head thereof abutting against one side of the bracket, and a correspondingly threaded nut 42 is mounted on the shank of the bolt at the other side of the bracket. The lever T is normally in position holding the slide Q in its outer position, and the lever is held by the bolt 40 from being actuated by the weight w, which bolt is secured in the desired adjustment by tightening the nut 42 which is of course loosened preparatory to the operation of the lever in the direction required to cause the gage-forming member P to move inwardly.

Means for measuring the descent of the cope during the lowering of the cope during the operation of the mold preferably comprises a vertically arranged rod *x* which (see Figs. 1, 2 and 5) extends loosely through a lug *k*³ formed on and externally of the upper end of the upper cope-casing-section *k* and loosely through the flange *K'* of the lower cope-casing-section *K* and rests upon 10 the uppermost or top solid chill-ring.

Upright rods *y* (see Figs. 1, 2, 6 and 7) which have externally screw-threaded ends are vertically arranged externally and spaced circumferentially of the chill *B* and extend 15 loosely through the flange *K'* of the lower cope-casing-section *K*, as shown in Fig. 1, and loosely through holes 46 formed in laterally projecting lugs 47 with which the top chill-ring is externally provided and 20 loosely through holes 48 formed in laterally and outwardly projecting horizontally arranged arms *H'* with which the receptacle *H* is externally provided, and preferably the rods *y* where they extend through the holes 25 48 are angular in cross-section, and the said holes are correspondingly angular and conform to the said angular portions of the rods so that turning of the rods is prevented.

Nuts 50 are mounted on the rods *y* above 30 the flange *K'* of the cope-casing-section *K'*, and nuts 52 are mounted on the said rods next under the projecting arms or members *H'* of the receptacle *H*. The receptacle *H* is normally detachably secured to the drag- 35 casing *E* preferably by bolts 53 and nuts 54 (see Figs. 1 and 7). The bolts 53 extend vertically through the receptacle-arms *H'* and flanges *e'* and *E'* and are arranged with their heads at the under side of the said 40 receptacle - arms, and the nuts 54 are mounted on the shanks of the said bolts at the top of the flange *E'*. The rods *y* and engaging nuts 50 and 52 suspend the receptacle *H* from the cope when the receptacle is detached from the drag-casing by removing the nuts 54 and bolts 53. The rods *y* and the engaging nuts 50 and 52 form an operative connection therefore between the receptacle *H* and the cope, 45 and the cope and the said receptacle together with the loose sand or material *g* and *f*, head or partition *F*, bodies of loam-sand *A'* *a'* and the casting can be lowered simultaneously while the chill and drag-casing 50 remain stationary, and the cope and receptacle are lowered by gravity assisted by a proper manipulation of the nuts 50 upon turning the nuts *O* in the direction required to permit the cope to lower. In the normal 55 and upper position of the cope the receptacle *H* abuts against the under side of the flange *e'* of the bottom *e* of the drag-casing, and hence upward displacement of the cope during the pouring of the mold is prevented.

60 Preparatory to any lowering of the re-

ceptacle *H* continuity in the laterally extending portion of the runner-gate *a*² is interrupted at the junction of the casing *E* with the body of loam-sand *a'* by a suitably applied and suitably operated cut-off which 70 preferably comprises a vertically arranged metal bar 60 very clearly shown in Fig. 5 and engaging a correspondingly arranged guide-way 62 formed in the runner-gate-casing *E*² below the said portion *a*² of the 75 runner-gate, and the cut-off 60 is normally in its lower and inoperative position below the runner-gate and is actuated upwardly at the proper time into or against the top wall of the laterally extending portion *a*² of the 80 runner-gate to separate any molten metal within the said portion of the runner-gate where the latter extends into the body of loam or sand *a'* from any metal in the runner-gate where the latter is arranged 85 externally of the said body of loam-sand. To facilitate its operation the cut - off is beveled at its upper end, as at 63, and preferably the sloping surface 63 is so arranged that during the operation of the 90 cut - off the said sloping surface tends to shove back any metal within the runner-gate externally of the body of loam-sand *a'*.

The means for actuating the cut-off 60 consists preferably of a vertically swinging 95 lever 64 which is fulcrumed, as at 65, to the runner-gate-casing *E*² and has one arm thereof extending under the lower end of and supporting the cut-off while the other arm of the lever is engaged on top by a 100 downwardly shifttable rod 66 which extends to the upper end of the pit 35 where it is manipulated as required to actuate the cut-off upwardly.

To space apart the receptacle *H* and the 105 cope *C* (see Figs. 1, 6 and 7) vertically arranged tubes 70 embrace the rods *y* and rest at their lower ends upon the arms *H'* of the receptacle *H*, which tubes are screw-threaded externally at their upper ends, and correspondingly internally screw-threaded sleeves 110 72 (see Fig. 1) are screwed onto the upper ends of the tubes and engage the under side of the flange *K'* of the lower cope-casing-section *K*. Obviously the tubes 70 and engaging sleeves 72 constitute adjustable spacing 115 means between the cope and receptacle *H* and the said tubes act to depress the said receptacle during any lowering of the cope while the cope engages the upper ends of the sleeves, but it will also be observed that the cope may be lowered independently of the remaining portions of the mold by properly manipulating the nuts *O* and 50 and sleeves 120 72 if the receptacle is supported independently of the cope, as, for instance, when it is detachably secured to the drag-casing by the bolts 53 and nuts 54.

Briefly described the operation of my improved mold is as follows:—By manipulating 125

130

the nuts O and 50 and sleeves 72 the cope is properly adjusted relative to the chill and the tubes 70 and sleeves 72 form a stiff but adjustable spacing device between the cope 5 and the receptacle whereupon the bolts 53 and nuts 54 are removed to detach the receptacle H from the drag-casing. The molten metal employed in casting a roll is introduced through the runner-gate to the drag-cavity 10 a, filling the said cavity and then rising into and filling the chill and then rising into and within the cope-chamber 13 until the level of the molten metal within the cope-chamber has risen as far as the upper end of the lower 15 cope-part. The upper cope-part is kept off the mold preparatory to the pouring of the mold so that the operators or attendants can skim off any dirt or dross appearing at the level of the molten metal when the said level 20 rises to the upper end of the lower cope-part. When the molten metal has had all the dross and dirt skimmed therefrom and the fed metal has settled down from the lower cope-part to nearly fully feed the chill the upper 25 cope-part is placed and fastened in position upon the lower cope-part, and the cope-chamber (including the feeding head h) is then filled to the upper end of the upper mold-part by pouring molten metal into the 30 feeding head from above after which by the use of a feeding rod worked up and down round the wobble-forming portion and inner end or main portion of the roll-neck to be cast within the cope a good union of the 35 metal below the wobble and the metal introduced from above is effected. The cut-off 60 is of course actuated into its upper and operative position as soon as the mold is poured. The molten metal introduced into 40 the mold is permitted to stand until it shall have formed a suitable shell or crust in the chill whereupon the cope and the receptacle H are lowered, permitting the flow of loose material f through the perforations or passageways e⁴ in the stationary head or bottom e into the said receptacle, thereby resulting in the descent of the head or partition F and the bodies of loam-sand a' and A' and with them the casting formed in the mold, so as 50 to insure the maintenance of the beads or ribs, which are formed externally of the crust or shell and next over the sloping seats of the chill-rings, in contact with the said seats until after the contraction has ceased, 55 or until after the maximum descent of the roll-body-forming portion of the casting on the sloping seat-forming surfaces of the sectional chill-rings r, upon which surfaces the casting is wholly supported after the maximum contraction of the casting. If pressure 60 is to be exerted downwardly upon the upper end of the roll-body-forming metal to form a good union between the upper neck and the roll-body, or for other reasons, the cope

is lowered independently of the remaining 65 portions of the mold by a proper manipulation of the nuts O and 50 and sleeves 72 upon holding the receptacle H temporarily stationary in any suitable manner. When the peripheral crust or shell of the roll-body has 70 formed in the chill the lever T is rendered free to be actuated by the weight w upon loosening the nut 42 on the bolt 40 whereupon the action of the said weight actuates the said lever in the direction required to 75 shift the member P into the chill as far as the horizontal contraction of the roll-body-forming portion of the casting will permit, and the coöperation of the scale 37 and pointer t measures and indicates the distance which 80 the said member P has moved into the chill and consequently the amount of horizontal contraction of the casting.

The descent of the cope is, as already stated, indicated by the additional distance 85 which the rod x projects above the cope upon the lowering of the cope in the operation of the mold.

In removing the casting from the mold the cope and the nuts O, m and 50 and sleeves 90 72 are of course first removed whereupon the top chill-ring can readily be removed and then the sectional chill-rings and solid chill-rings are readily removed one at a time and in order. 95

What I claim is:—

1. In a mold for casting a chilled roll, a vertically arranged annular chill comprising solid rings which are arranged in line vertically and provided each at its lower 100 end and internally with a recess extending circumferentially of the chill, which rings are also each provided internally next above the said recess with a downwardly and inwardly sloping seat-forming surface 105 extending circumferentially of the chill, and a ring occupying the said recess and divided vertically into sections and provided internally with a downwardly and inwardly sloping seat-forming surface arranged flush at its upper end with the first-mentioned sloping surface. 110
2. In a roll-casting mold, a vertically arranged annular chill comprising solid rings arranged in line vertically and provided 115 each at its lower end and internally with a recess extending circumferentially of the chill, which rings are also each provided internally and above the said recess with a downwardly and inwardly sloping seat-forming surface extending circumferentially of the chill, and a ring occupying the said recess and divided vertically into sections and provided internally with a downwardly and inwardly sloping seat-forming surface arranged flush at its upper end with the first-mentioned sloping surface, and each section of the said sectional ring having a de- 120 125

pending flange whose inner side overlaps an upright laterally and outwardly facing shoulder formed on the next lower solid ring.

3. In a roll-casting mold, a vertically arranged annular chill comprising solid rings arranged in line vertically and provided each internally with a recess extending circumferentially of the chill, which rings are also each provided internally next above the said recess with a downwardly and inwardly sloping seat-forming surface extending circumferentially of the chill, and a ring occupying the said recess and divided vertically into sections and provided internally with a downwardly and inwardly sloping seat-forming surface arranged flush at its upper end with the first-mentioned sloping surface, with the upper of adjacent sectional rings overhanging the seat-forming sloping surface of the next lower solid ring.

4. In a roll-casting mold, a vertically arranged annular chill comprising solid rings arranged in line vertically and provided each internally with a recess extending circumferentially of the chill, which rings are also each provided internally and above the said recess with a downwardly and inwardly sloping seat-forming surface extending circumferentially of the chill, and a ring occupying the said recess and divided vertically into sections, said sectional ring being provided internally with a downwardly and inwardly sloping seat-forming surface extending circumferentially of the said ring and smaller diametrically than the first-mentioned sloping surface, and the sections of the sectional ring embracing the extreme upper end of the next lower solid ring.

5. In a roll-casting mold, a vertically arranged annular chill comprising solid rings arranged in line vertically and provided each internally with a recess extending circumferentially of the chill, which rings are also each provided internally and above the said recess with a downwardly and inwardly sloping seat-forming surface extending circumferentially of the chill, said recess having its surrounding wall sloping downwardly and outwardly, and a ring occupying the said recess and divided vertically into sections and provided internally with a downwardly and inwardly sloping seat-forming surface arranged flush at its upper end with the first-mentioned sloping surface, said last-mentioned ring conforming to the surrounding wall of the said recess, and the upper of adjacent sectional rings resting upon the next lower solid ring.

6. In a roll-casting mold, a vertically arranged annular chill comprising superimposed solid rings provided each internally with a recess extending circumferentially of the chill, which rings are also each provided internally and above the said recess with a

downwardly and inwardly sloping seat-forming surface extending circumferentially of the chill, and a ring occupying the said recess and divided vertically into sections and provided internally with a downwardly and inwardly sloping seat-forming surface arranged flush at its upper end with the first-mentioned sloping surface, and the lower of adjacent solid rings being provided externally with an upwardly facing shoulder extending circumferentially of the chill and forming a bearing for the upper of the said adjacent rings.

7. In a roll-casting mold, a vertically arranged chill having a circular chamber extending from end to end of the chill and provided internally with downwardly and inwardly sloping seats extending circumferentially of the chill and arranged at different elevations respectively, with the lower portions of the said seats formed by suitably supported sectional rings, and with the upper portions of the said seats formed by suitably supported solid rings.

8. In a roll-casting mold, a vertically arranged chill having a circular chamber extending from end to end of the chill and provided internally with downwardly and inwardly sloping seats extending circumferentially of the chill and arranged at different elevations respectively, and each seat being formed by and internally of a plurality of suitably supported rings extending circumferentially of the chill.

9. In a roll-casting mold, a vertically arranged chill having a circular chamber extending from end to end of the chill and formed by solid rings and rings divided vertically into sections alternating with the solid rings, with the sections of each sectional ring embracing the adjacent portion of an adjacent solid ring.

10. In a roll-casting mold, a vertically arranged chill having a circular chamber extending from end to end of the chill and provided internally with downwardly and inwardly sloping seats extending circumferentially of the chill and arranged at different elevations respectively and the lower portion of each seat being formed by a suitably supported sectional ring, and the upper portion of the said seat being formed by a suitably supported solid ring which embraces the said sectional ring.

11. In a roll-casting mold, a vertically arranged chill having a circular chamber extending from end to end of the chill and provided internally with downwardly and inwardly sloping seats extending circumferentially of the chill and arranged at different elevations respectively, with the lower portions of the said seats formed by suitably supported sectional rings, with the upper portions of the said seats formed by suitably supported solid rings provided in their upper ends with recesses forming outlets for air and

gases, which recesses are spaced circumferentially of the chill and extend from the exterior of the chill into close proximity to but arranged wholly exteriorly of the aforesaid chamber, and the joint between each sectional ring and the recessed upper end of the next lower solid ring being loose enough adjacent the inner ends of the recesses in the said end of the said solid ring to permit the escape of air and gases to the said recesses from the aforesaid chamber.

12. In a roll-casting mold, a vertically arranged chill having a circular chamber extending from end to end of the chill and provided internally with downwardly and inwardly sloping seats extending circumferentially of the chill and arranged at different elevations respectively, with the lower portions of the said seats formed by suitably supported sectional rings, with the upper portions of the said seats formed by suitably supported solid rings, and with each sectional ring embraced by a solid ring.

13. In a roll-casting mold, a vertically arranged chill having a circular chamber extending from end to end of the chill and provided internally with downwardly and inwardly sloping seats extending circumferentially of the chill and arranged at different elevations respectively, with the lower portions of the said seats formed by sectional rings, with the upper portions of the said seats formed by solid rings, with the upper of adjacent sectional rings resting on the next lower solid ring, and with each solid ring resting on a sectional ring.

14. In a roll-casting mold, a vertically arranged chill having a circular chamber extending from end to end of the chill and provided internally with downwardly and inwardly sloping seats extending circumferentially of the chill and arranged at different elevations respectively, with the lower portions of the said seats formed by sectional rings, with the upper portions of the said seats formed by solid rings, with each sectional ring embraced by a solid ring, with the upper of adjacent sectional rings resting on the next lower solid ring and overlapped on top by the solid ring embracing it, and with the upper of adjacent solid rings having bearing on the next lower solid ring.

15. In a roll-casting mold, a vertically arranged chill having a circular chamber extending from end to end of the chill and provided internally with downwardly and inwardly sloping seats extending circumferentially of the chill and arranged at different elevations respectively, with the lower portions of the said seats formed by suitably supported sectional rings, with the upper portions of the said seats formed by suitably supported solid rings, and with the relative dimensions of the seat-forming surfaces of the solid rings and the seat-forming surfaces

of the sectional rings being such that the casting produced in the mold shall after wholly cooling or contracting rest entirely upon the seat-forming surfaces of the sectional rings.

16. In a roll-casting mold, an upright chill provided with a chamber extending from end to end of the chill; a lower mold-part or drag having a cavity which is provided with an inlet and communicates with the chill-chamber at the lower end of the chill; an upper mold-part or cope provided with a chamber which communicates with the chill-chamber at the upper end of the chill, said cope being movable vertically independently of the chill, and a member arranged at one side of the cope and instrumental in measuring the descent of the cope during the lowering of the cope, said descent-measuring member being supported at the upper end of the chill independently of the cope.

17. In a roll-casting mold, a suitably supported upright chill provided with a chamber extending from end to end of the chill; a lower mold-part or drag having a cavity which is provided with an inlet and communicates with the chill-chamber at the lower end of the chill; an upper mold-part or cope provided with a chamber which communicates with the chill-chamber at the upper end of the chill, said cope being supported as required to render it capable of being lowered and comprising a casing which is provided at its upper end with a laterally and outwardly projecting member, and an upright rod extending loosely through the said projecting member and resting upon the upper end of the chill.

18. In a roll-casting mold, a suitably supported lower mold-part or drag provided with a cavity having an inlet; an upright chill having a circular chamber extending from end to end of the chill and communicating at its lower end with the drag-cavity; a cope having a chamber which extends from end to end of the cope and communicates with the chill-chamber at the upper end of the chill, said cope comprising an upper cope-part and a lower cope-part, with the latter adapted to be lowered within the chill and provided externally and a suitable distance above the chill with a laterally and outwardly projecting member, with the upper cope-part resting upon and removably secured to the lower cope-part and provided at its upper end with a laterally and outwardly projecting member; means supporting the cope and arranged to be lowered to accommodate a descent of the cope, and an upright member resting upon the upper end of the chill and extending loosely through the aforesaid projecting members of the cope.

19. A roll-casting mold comprising a suitably supported upright chill; a suitably supported upper mold-part or cope arranged at the upper end of the chill; a lower mold-part

- or drag having a suitably supported depressible portion which is provided with a cavity communicating with the chill, said drag also comprising the following:—a stationary casing 5 extending circumferentially of the said depressible portion of the drag; a runner-gate which extends through the casing and communicates with the said cavity, the cavity-connecting portion of the runner-gate being adapted to lower with the aforesaid depressible portion of the drag, and a 10 cut-off for interrupting continuity in the runner-gate at the point required to avoid obstruction to the descent of the aforesaid depressible portion of the drag by metal within the stationary portion of the runner-gate, said cut-off being normally arranged below the last-mentioned portion of the runner-gate and movable upwardly into position obstructing the runner-gate. 15
20. A roll-casting mold comprising an upright chill; an upper mold-part or cope arranged at the upper end of the chill; a lower mold-part or drag having a suitably supported depressible portion which is provided with a cavity communicating with the chill, said drag also comprising the following:—a stationary casing surrounding the said depressible portion of the drag; a runner-gate 25 which extends through the casing and communicates with the said cavity, the cavity-connecting portion of the runner-gate being adapted to lower with the aforesaid depressible portion of the drag; a cut-off for interrupting continuity in the runner-gate at the 30 point required to avoid obstruction to the descent of the aforesaid depressible portion of the drag by metal within the stationary portion of the runner-gate, said cut-off being normally arranged below the last-mentioned portion of the runner-gate and movable upwardly into position obstructing the runner-gate, and a lever supporting and arranged to 35 actuate the cut-off. 40
45. 21. In a roll-casting mold, a suitably supported lower mold-part or drag provided with a cavity having an inlet; a vertically arranged chill having a circular chamber extending from end to end of the chill and communicating at its lower end with the drag-cavity; a cope having a chamber which 50 communicates with the chill-chamber at the upper end of the chill, said cope comprising a casing which is provided externally and a suitable distance above the chill with a laterally and outwardly projecting annular flange; upright rods spaced circumferentially of the chill and supported independently of the cope and extending through the said flange and screw-threaded where they 55 extend through the flange; nuts mounted on the said screw-threaded portions of the rods and extending through and turnable within the flange, which nuts are provided at the 60 lower ends and externally with upwardly 65

facing annular shoulders arranged below the said flange, and antifriction bearings interposed between the said shoulders and the flange. 70

22. In a roll-casting mold, a suitably supported lower mold-part or drag provided with a cavity having an inlet and comprising a stationary casing; a vertically arranged chill having a circular chamber extending from end to end of the chill and communicating 75 at its lower end with the drag-cavity, which chill is composed of superimposed rings; a suitably supported cope having a chamber which communicates with the chill-chamber at the upper end of the chill; vertically arranged screw-threaded rods spaced circumferentially of the chill and connected to the drag-casing and extending through the top chill-ring; nuts mounted on the said rods and preventing upward displacement of the said 80 top chill-ring, and nuts mounted on the rods above the first-mentioned nuts and supporting the cope. 85

23. In a roll-casting mold, a suitably supported lower mold-part or drag provided with a cavity having an inlet; a vertically arranged chill having a circular chamber extending from end to end of the chill and communicating at its lower end with the drag-cavity, which chill is composed of superimposed 90 rings, with the uppermost or top ring provided externally with laterally and outwardly projecting lugs spaced circumferentially of the chill; a cope having a chamber which communicates with the chill-chamber at the upper end of the chill; vertically arranged rods spaced circumferentially of the chill and extending through the aforesaid lugs and screw-threaded above the said lugs; nuts mounted on the said screw-threaded 95 portions of the rods and resting on the said lugs; compressible members interposed between the said nuts and the lugs, and nuts mounted on the rods above the first-mentioned nuts and supporting the cope. 100

24. In a roll-casting mold, a suitably supported lower mold-part or drag provided with a cavity having an inlet, said drag comprising a casing provided at its upper end with laterally and outwardly projecting lugs spaced 105 circumferentially of the drag; a vertically arranged chill having a circular chamber extending from end to end of the chill and communicating at its lower end with the drag-cavity, which chill is composed of superimposed rings, with the uppermost or top ring provided externally with laterally and outwardly projecting lugs spaced circumferentially of the chill; a suitably supported cope having a chamber which communicates with the chill-chamber at the upper end of the chill; vertically arranged rods spaced circumferentially of the chill and extending through the lugs in the drag-casing and through the lugs in the top chill-ring, said rods being 110 115 120 125 130

screw-threaded at their lower ends and screw-threaded above the lugs of the top chill-ring; nuts mounted on the said rods under the lugs of the drag-casing; nuts mounted on the said 5 rods and resting on the lugs of the top chill-ring, and compressible members interposed between the last-mentioned lugs and the last-mentioned nuts.

25. In a roll-casting mold, the combination, with a stationary vertically arranged 10 chill; an upper mold-part or cope arranged and adapted to be lowered within the chill, and a lower mold-part or drag comprising a casing and having a cavity which communicates 15 with the chill; a runner-gate which has an upper upright portion and a lower portion which extends laterally from the lower end of the upright portion through the drag-casing and communicates at its discharging end 20 with the aforesaid cavity; a casing surrounding the outer end of the lower portion of the runner-gate and formed on the drag-casing under the upright portion of the runner; a casing surrounding the upright portion of the 25 runner-gate and rigid with the casing of the laterally extending portion of the runner-gate, and the first-mentioned runner-gate-casing comprising an upright removable section arranged opposite and facing the outer 30 end of the said laterally extending lower portion of the runner-gate.

26. A roll-casting mold comprising a suitably supported upright chill; a suitably supported upper mold-part or cope arranged at 35 the upper end of the chill, and a lower mold-part or drag having a suitably supported de- 40 pressible portion which is provided with a cavity communicating with the chill, said drag also comprising the following:—a sta- 45 tionary casing surrounding the said de- 50 pressible portion of the drag and having a per- 55forated bottom which is arranged a suitable 60 distance below the drag-cavity; a runner- 65 gate which extends through the casing and 70 communicates with the said cavity, the 75 cavity-connecting portion of the runner-gate 80 being adapted to lower with the aforesaid 85 de- 90 pressible portion of the drag; a cut-off for 95 interrupting continuity in the runner-gate 100 at the point required to avoid obstruction to 105 the descent of the aforesaid de- 110 pressible portion of the drag by metal within the 115 stationary portion of the runner-gate; a parti- 120 tion-forming head arranged to bear the aforesaid 125 de- 130 pressible portion of the drag and adapted to be lowered; a body of loose fluent material interposed between the head or partition and aforesaid casing-bottom, and a receptacle supported as required to render it capable of being lowered, said receptacle being arranged to receive material discharged downwardly through the aforesaid perforated bottom during the descent of the receptacle.

65 27. A roll-casting mold comprising a suit-

ably supported upright chill; a suitably supported upper mold-part or cope, and a lower mold-part or drag having a suitably supported de- 70 pressible portion which is provided with a cavity which communicates with the chill, said drag also comprising the following:—a stationary casing surrounding the said de- 75 pressible portion of the drag and having a perforated bottom which is arranged a suitable distance below the drag-cavity; a 80 partition-forming head arranged to bear the aforesaid de- 85 pressible portion of the drag and adapted to be lowered; a body of loose fluent material interposed between the head or partition and the aforesaid casing-bottom, and a receptacle supported as required to render it capable of being lowered and arranged to receive material discharged downwardly through the aforesaid perforated bottom during the descent of the receptacle. 85

28. A roll-casting mold comprising a suitably supported upright chill; a suitably supported upper mold-part or cope, and a lower mold-part or drag having a suitably supported de- 90 pressible portion which is provided with a cavity which communicates with the chill, said drag also comprising the following:—a stationary casing surrounding the said de- 95 pressible portion of the drag and having a perforated bottom which is arranged a suitable distance below the drag-cavity; a partition-forming head arranged to bear the aforesaid de- 100 pressible portion of the drag and adapted to be lowered; a body of loose fluent material interposed between the head or partition and the aforesaid casing-bottom; a receptacle supported as required to render it capable of being lowered, said receptacle being arranged to receive material discharged downwardly through the aforesaid perforated bottom, and means for detachably fastening the said receptacle to the aforesaid casing. 105

29. A roll-casting mold comprising a suitably supported upright chill; a suitably supported upper mold-part or cope, and a lower mold-part or drag having a suitably supported de- 110 pressible portion which is provided with a cavity communicating with the chill, said drag also comprising the following:—a stationary casing surrounding the said de- 115 pressible portion of the drag and having a perforated bottom which is arranged a suitable distance below the drag-cavity and provided at its upper side with an annular 120 recess having upwardly diverging walls and outlets at the lower ends of the said walls; a partition-forming head arranged to bear the aforesaid de- 125 pressible portion of the drag and adapted to be lowered; a body of loose fluent material interposed between the head or partition and the aforesaid casing-bottom, and a receptacle supported as required to render it capable of being lowered, said receptacle being arranged to receive material 130

discharged downwardly through the aforesaid outlets during the descent of the receptacle.

30. A roll-casting mold comprising a suitably supported upright chill; a suitably supported upper mold-part or cope, and a lower mold-part or drag having a suitably supported compressible portion which is provided with a cavity communicating with the chill, said drag also comprising the following:—a stationary casing surrounding the said compressible portion of the drag and having a perforated bottom which is arranged a suitable distance below the drag-cavity; a partition-forming head arranged to bear the aforesaid compressible portion of the drag and adapted to be lowered; a body of loose fluent material interposed between the head or partition and the aforesaid casing-bottom; a receptacle supported as required to render it capable of being lowered, said receptacle being arranged to receive material discharged downwardly through the aforesaid perforated bottom during the descent of the receptacle, and suitably applied bolts and nuts detachably fastening the said receptacle to the aforesaid casing.

31. A roll-casting mold comprising a suitably supported upright chill; a suitably supported upper mold-part or cope, and a lower mold-part or drag having a suitably supported compressible portion which is provided with a cavity communicating with the chill, said drag also comprising the following:—a stationary casing surrounding the said compressible portion of the drag and having a perforated bottom which is arranged a suitable distance below the drag-cavity; a partition-forming head arranged to bear the aforesaid compressible portion of the drag and adapted to be lowered; a body of loose fluent material interposed between the head or partition and the aforesaid casing-bottom, and a receptacle supported as required to render it capable of being lowered, said receptacle slidably embracing the said bottom and arranged to receive material discharged downwardly through the bottom during the descent of the receptacle.

32. A roll-casting mold comprising a suitably supported vertically arranged chill; a suitably supported upper mold-part or cope, and a lower mold-part or drag having two superimposed compressible bodies provided with a cavity which is partially formed in each of the said compressible bodies and communicates with the chill, said drag also comprising the following:—a stationary casing surrounding the said compressible bodies and having a perforated bottom which is arranged a suitable distance below the drag-cavity; means for detachably fastening the upper of the said superimposed compressible bodies to the casing; a runner-gate communicating with the aforesaid cavity, the cavity-connecting portion of the runner-gate being adapted to lower with the aforesaid superimposed compressible bodies, and a head arranged under the lower of the said superimposed compressible bodies and supported as required to render it capable of being lowered.

33. A roll-casting mold comprising a suitably supported vertically arranged chill; a suitably supported upper mold-part or cope arranged at the upper end of the chill, and a lower mold-part or drag having a suitably supported compressible portion which is provided with a cavity communicating with the chill, said drag also comprising the following:—a stationary casing surrounding the said compressible portion of the drag and having a perforated bottom which is arranged a suitable distance below the drag-cavity; a runner-gate communicating with the said cavity, the cavity-connecting portion of the runner-gate being adapted to lower with the aforesaid compressible portion of the drag; a body of loose fluent material interposed between the said compressible portion of the drag and aforesaid casing-bottom, and a receptacle supported as required to render it capable of being lowered, said receptacle being arranged to receive material discharged downwardly through the aforesaid perforated bottom during the descent of the receptacle.

34. A roll-casting mold comprising a suitably supported vertically arranged chill; a suitably supported upper mold-part or cope arranged at the upper end of the chill, and a lower mold-part or drag having two superimposed compressible bodies provided with a cavity which is partially formed in each of the said compressible bodies and communicates with the chill, said drag also comprising the following:—a stationary casing surrounding the said compressible bodies; means for detachably fastening the upper of the said superimposed compressible bodies to the drag-casing; a runner-gate communicating with the aforesaid cavity, the cavity-connecting portion of the runner-gate being adapted to lower with the aforesaid superimposed compressible bodies, and a head arranged under the lower of the said superimposed compressible bodies and supported as required to render it capable of being lowered.

35. A roll-casting mold comprising a suitably supported vertically arranged chill; a suitably supported upper mold-part or cope arranged at the upper end of the chill, and a lower mold-part or drag having two superimposed compressible bodies provided with a cavity which is partially formed in each of the

- 5 said depressible bodies and communicates with the chill, said drag also comprising the following:—a drag-cavity which communicates with the chill and is formed by two superimposed bodies adapted to be lowered; a stationary casing surrounding the said superimposed depressible bodies; endwise withdrawable pins supported from the said casing and extending into the upper of the said superimposed depressible bodies, and a head arranged under the lower of the said superimposed depressible bodies and supported as required to render it capable of being lowered.
- 10 36. A roll-casting mold comprising a suitably supported vertically arranged chill; a suitably supported upper mold - part or cope, and a lower mold-part or drag having a suitably supported depressible portion which is provided with a cavity communicating with the chill, said drag also comprising the following:—a stationary casing surrounding the said depressible portion of the drag and having a bottom which is arranged a suitable distance below the drag-cavity, which bottom is provided with two annular recesses arranged at the upper side and lower side respectively of the bottom and in communication with each other; a body of loose fluent material between the said bottom and the aforesaid depressible portion of the mold; a receptacle embracing the said bottom and supported as required to render the receptacle capable of being lowered, and
- 15 loose fluent material occupying any space between the aforesaid casing-bottom and the bottom of the receptacle.
- 20 37. A roll-casting mold comprising a suitably supported vertically arranged chill; a suitably supported upper mold-part or cope arranged at the upper end of the chill, and a lower mold-part or drag having a suitably supported depressible portion which is provided with a cavity communicating with the chill, said drag also comprising the following:—a stationary casing surrounding the said depressible portion of the drag and having a perforated bottom which is arranged a suitable distance below the drag-cavity, which bottom is provided with recesses arranged in line vertically and formed in the upper side and lower side respectively of the bottom and in communication with each other; a body of loose fluent material between the said bottom and the aforesaid depressible portion of the drag; a receptacle embracing the said bottom and supported as required to render the receptacle capable of being lowered, and a loose fluent material arranged and adapted to be lowered within
- 25 the chill, and a lower mold-part or drag having a suitably supported depressible portion which is provided with a cavity communicating with the chill, said drag also comprising the following:—a stationary casing surrounding the said depressible portion of the drag and having a perforated bottom which is arranged a suitable distance below the drag-cavity; a runner-gate which extends through the said casing and communicates with the cavity, the cavity-connecting portion of the runner-gate being adapted to lower with the aforesaid depressible portion of the body; a body of loose fluent material between the said depressible portion of the drag and the aforesaid bottom, and a receptacle arranged to receive material discharged downwardly through the aforesaid perforated bottom during the descent of the receptacle and operatively connected with the cope.
- 30 39. In a roll-casting mold comprising a suitably supported vertically arranged chill; a suitably supported upper mold-part or cope arranged and adapted to be lowered within the chill, and a lower mold-part or drag having a suitably supported depressible portion which is provided with a cavity communicating with the chill, said drag also comprising the following:—a stationary casing surrounding the said depressible portion of the drag and having a perforated bottom which is arranged a suitable distance below the drag-cavity; a runner-gate which extends to and communicates with the aforesaid cavity, the cavity-connecting portion of the runner-gate being adapted to lower with the aforesaid depressible portion of the drag; loose fluent material between the said depressible portion of the drag and the aforesaid bottom; a receptacle having laterally and outwardly projecting arms spaced circumferentially of the drag, which receptacle is arranged to receive material discharged downwardly through the aforesaid perforated bottom during the descent of the receptacle; screw-threaded rods suspended from the cope and extending through the aforesaid arms, and nuts on the rods at the under sides of the arms.
- 35 40. A roll-casting mold comprising a suitably supported upright chill; a suitably supported upper mold-part or cope arranged and adapted to be lowered within the chill, and a lower mold-part or drag having a suitably supported depressible portion which is provided with a cavity communicating with the chill, said drag also comprising the following:—a stationary casing which surrounds the said depressible portion of the drag and has a perforated bottom which is arranged a suitable distance below the drag-cavity; loose fluent material between the said bottom and the aforesaid depressible portion of the drag; a receptacle having lat-

erally and outwardly projecting portions and arranged to receive material discharged downwardly through the aforesaid perforated bottom during the descent of the receptacle; vertically arranged tubes resting on the said projecting portions of the receptacle and screw-threaded externally at their upper ends; correspondingly internally screw-threaded sleeves mounted on the 10 threaded upper ends of the tubes and overlapped on top by the cope, and rods extending through the said tubes and suspended from the cope, which rods are operatively connected with the aforesaid receptacle.

41. A roll-casting mold comprising a suitably supported upright chill; a suitably supported upper mold-part or cope arranged and adapted to be lowered within the chill, and a lower mold-part or drag having a suitably supported depressible portion which is provided with a cavity communicating with the chill, said drag also comprising the following:—a stationary casing surrounding the said depressible portion of the drag and having a perforated bottom which is arranged a suitable distance below the drag-cavity; loose fluent material between the said bottom and the aforesaid depressible portion of the drag; a receptacle having laterally and outwardly projecting portions and arranged to receive material discharged downwardly through the aforesaid perforated bottom during the descent of the receptacle; vertically arranged tubes resting on the 20 said projecting portions of the receptacle; vertically adjustable members borne by the upper ends of the tubes overlapped on top by the cope, and rods extending through the said tubes and suspended from the cope, 30 which rods are operatively connected with the aforesaid receptacle.

42. In a roll-casting mold comprising a suitably supported upright chill; a suitably supported upper mold-part or cope arranged and adapted to be lowered within the chill, and a lower mold-part or drag having a suitably supported depressible portion

which is provided with a cavity communicating with the chill, said drag also comprising the following:—a stationary casing 50 which surrounds the said depressible portion of the drag and has a perforated bottom which is arranged a suitable distance below the drag-cavity; loose fluent material between the said bottom and the aforesaid de- 55 pressible portion of the drag; a receptacle having laterally and outwardly projecting arms spaced circumferentially of the receptacle, which receptacle is suspended from the cope and arranged to receive material discharged downwardly through the aforesaid perforated bottom during the descent of the receptacle, and a spacing device between each receptacle-arm and the cope.

43. A roll-casting mold comprising a suitably supported upright chill; a suitably supported upper mold-part or cope arranged and adapted to be lowered within the chill, and a lower mold-part or drag having a suitably supported depressible portion which is 70 provided with a cavity communicating with the chill, said drag also comprising the following:—a stationary casing surrounding the said depressible portion of the drag and having a perforated bottom arranged a suitable 75 distance below the drag-cavity; loose fluent material between the said bottom and the aforesaid depressible portion of the drag; a receptacle having laterally and outwardly projecting arms spaced circumferentially of 80 the receptacle, which receptacle is arranged to receive material discharged downwardly through the aforesaid perforated bottom during the descent of the receptacle, and an adjustable spacing device between each receptacle-arm and the cope.

In testimony whereof, I sign the foregoing specification, in the presence of two witnesses.

RALPH H. WEST.
